UNITED STATES PATENT OFFICE.

OTTO E. MAUL, OF MOUNT VERNON, NEW YORK.

DESIGN FOR MATERIAL FOR APPLIQUÉ WORK.

46,000.

Specification for Design.

Patented June 23, 1914.

Application filed April 6, 1914. Serial No. 830,055. Term of patent 3½ years.

To all whom it may concern:

Be it known that I, OTTO E. MAUL, a citizen of the United States, and a resident of Mount Vernon, in the county of Westchester and State of New York, have invented a new, original, and ornamental Design for Material for Appliquéd Work, of which the following is a specification, reference being had to the accompanying drawing, forming part thereof.

The figure is a plan view of a portion of the material illustrating my new design.

I claim:

The ornamental design for material for appliquéd work, as shown.

OTTO E. MAUL.
